UNITED STATES PATENT OFFICE.

EDWIN H. SMYTHE, OF CHICAGO, ILLINOIS, ASSIGNOR TO WESTERN ELECTRIC COMPANY, OF CHICAGO, ILLINOIS, A CORPORATION OF ILLINOIS.

ALTERNATING-CURRENT POLE-CHANGER CIRCUIT.

No. 835,870.

Specification of Letters Patent.

Patented Nov. 13, 1906.

Application filed February 1, 1906. Serial No. 298,917.

To all whom it may concern:

Be it known that I, EDWIN H. SMYTHE, a citizen of the United States, residing at Chicago, in the county of Cook and State of Illinois, have invented a certain new and useful Improvement in Alternating-Current Pole-Changer Circuits, of which the following is a full, clear, concise, and exact description.

My invention relates to an electric converter, and has for its object to provide an improved and efficient arrangement of circuits and apparatus for transforming alternating current into pulsating current.

Generally speaking, my invention contemplates an electromagnet adapted to operate mechanism, such as a vibratory pole-changer, for separating alternating current from a suitable source into positive or negative pulsations. The electromagnet is preferably polarized and included in the circuit leading from said alternating-current source, and switching mechanism is provided adapted to apply pulsations of either character developed by said pole-changer to a desired circuit, said mechanism being also adapted when operated to automatically close said alternating-current circuit through said magnet.

A feature of my invention consists in the provision of means, such as a condenser, in said alternating-current circuit for maintaining the pole-changer in tune with the alternating current, the condenser acting as a synchronizer.

Another feature of my invention consists in its special adaptability for use in connection with telephone-exchanges where the converter may be used to signal party-lines. I have found that by means of my invention a great saving may be made in the installation and equipment of private exchanges from which party-lines radiate, since the converter may be located at the private exchange, and but a single wire need be run from the main exchange for ringing purposes—that is, the one leading from the alternating-current generator—instead of the three heretofore necessary. The use of elaborate equipment at the private exchange is thus avoided.

I will describe my invention particularly by reference to the accompanying drawing,

which is a diagram illustrative of one embodiment of my invention.

The accompanying drawing illustrates my invention as applied to telephone-exchanges.

A party telephone-line A is shown extending in two limbs 1 2 from four substations I II III IV to a spring-jack terminal a at the private exchange or central office. The substation equipment is of the usual type, each limb having two ground branches from two substations containing signal-bells responsive to positive or negative pulsations of current, respectively, the bells of stations I and II being in ground branches leading from limb 1, while the bells of the remaining stations III 65 IV being in ground branches leading from limb 2. The branches may be controlled by normally open contacts of relays x in bridges of the line at the different substations in the usual manner.

A plug b, with a portion of its circuit, is shown at the private exchange for making connection with the line through the medium of spring-jack a. The conductors 3 4 of the plug-circuit lead through the levers and normal resting contacts of keys c c' c² c³, respectively, which are adapted when operated to ground one conductor of the plug-circuit and apply pulsating current to the other. The conductors 3 4 also lead through levers and 80 contacts of a key c⁴, adapted to apply alternating current to the plug-circuit.

A grounded generator G is located at the main exchange or central office, and a conductor 5 extends therefrom to a private exchange, where it is connected by conductors 6 6^a 6^b 6^c to extra contact-arms c⁵, one being carried by and insulated from one member of each of the switch-keys c c' c² c³. A normally open contact c⁶ is provided for each of the arms c⁵, said contacts c⁶ being connected by conductors 7 7^a 7^b 7^c with a conductor 8, leading to earth through the polarized magnet d of the converter E, a branch 9 leading from conductor 8 to the vibrating arm e' of the pole-changer E, which is adapted to be operated by magnet d. The moving arm e' is suitably connected to the armature d' of magnet d to partake of its movement. A conductor 10 leads from conductor 9 to the

outer arms e^2 e^3 of the pole-changer. Contact members e^4 e^5 of the pole-changer are normally mounted with their free ends lying between contacts e^2 e' and contacts e^3 e' , respectively. Contact e^4 of the pole-changer is connected by conductor 11 with the opposite outer contacts c^7 c^8 of keys c^2 c^3 , respectively, while contact e^5 is connected by conductor 12 with opposite outer contacts c^9 c^{10} of keys c c' , respectively, the remaining or opposite outer contacts of said keys being grounded.

The arm e' of the pole-changer is adapted when operated by the armature d' to alternately close contacts e^2 e^4 and e^3 e^5 , according as the differently directed or alternating waves of current pass through the magnet d , so that pulsations of one character—for example, positive—will be applied to conductor 11, while pulsations of opposite character—that is, of negative polarity—will be applied to conductor 12. Thus when the operator after plugging into the party-line desires to signal a station thereon—for example No. II—she depresses key c , whereupon limb 2 of the line is grounded and a circuit 5, 6, 7, and 8 is provided for the magnet d of the converter. The pole-changer is now operated and negative pulsations applied to limb 1 by way of conductor 12, contact c^9 , and conductor 3, whereupon the bell at station II is operated in the usual manner.

A conductor 13 may lead from conductor 5 to the outer contact of the alternating ringing-key c^4 , said conductor preferably including the usual resistance-lamp. The conductor 9 may also contain a resistance-lamp, if desired.

I also provide a synchronizer in the circuit 8, adapted to maintain the pole-changer in tune with the alternating current. This synchronizer preferably comprises a condenser C , which serves to counteract any self induction or reactance in magnet d .

I claim—

1. The combination with a party telephone-line extending from two substations to a central office, of signals at said stations responsive to positive and negative pulsating current, respectively, a conductor at the central office carrying alternating current, an electromagnetically-operated pole-changer, adapted to separate said alternating current into positive and negative pulsations, means for operating said pole-changer, and switching devices at the central office for applying pulsations of either character to the line.

2. The combination with an electric circuit containing signals responsive to positive and negative pulsating current, respectively, of a source of alternating current, a pole-changer adapted to separate current from said source into positive and negative pulsations, a polarized electromagnet adapted

when supplied with current from said source to operate said pole-changer, and switching mechanism adapted when operated to connect said source with said magnet and pole-changer, and to apply pulsations of either character to said circuit.

3. The combination with a party telephone-line extending from two substations to a spring-jack at a central office, of signals at the substations responsive to positive and negative pulsating current, respectively, a conductor at the central office carrying alternating current, a plug and plug-circuit for making connection with the spring-jack of said line, an electromagnetically-operated pole-changer at the central office for separating said alternating current into positive and negative pulsations, and switches in said plug-circuit adapted when operated to connect said conductor with said pole-changer to operate the same, one switch being also adapted to apply positive and the other negative pulsations to the line.

4. The combination with a party telephone-line extending from two substations to a spring-jack at a central office, of signals at said stations responsive to positive and negative pulsating current, respectively, a conductor at the central office carrying alternating current, a pole-changer adapted to separate said alternating current into positive and negative pulsations, a plug and plug-circuit for making connection with said spring-jack, mechanism for operating said pole-changer, and switch-keys at the central office controlling said mechanism and adapted to apply pulsations of either character to the line.

5. The combination with a main electric circuit, containing signals responsive to pulsating current, of a source of alternating current, a circuit therefor, mechanism adapted to separate current from said source into positive and negative pulsations, a polarized magnet in said alternating-current circuit adapted to operate said mechanism, means for maintaining said mechanism in tune with the alternating current, and means for applying said pulsations to said main circuit.

6. The combination with a main electric circuit, containing signals responsive to positive and negative pulsating current, respectively, of a source of alternating current, a pole-changer adapted to separate alternating current from said source into positive and negative pulsations, a polarized electromagnet in said alternating-current circuit, adapted to operate said pole-changer, a condenser in said circuit adapted to maintain the pole-changer in tune with the alternating current, and means for applying pulsations of either character to the main circuit.

7. The combination with a main exchange,

of a private exchange, a party telephone-line extending from two substations to said private exchange, signals at said substations responsive to positive and negative pulsating currents, respectively, a source of alternating current at the main exchange, a conductor leading from said source to the private exchange, electromagnetically-operated mechanism at the private exchange adapted to 5 separate the alternating current carried by

said conductor into positive and negative pulsations, and means for applying pulsations of either character to the line.

In witness whereof I hereunto subscribe my name this 30th day of January, A. D. 15 1906.

EDWIN H. SMYTHE.
